COMBINED BUCKET AND CLOSURE THEREFOR

George Yates, Jr., Glendale, Calif., assignor to Growth International Industries Corporation, Cleveland, Ohio

Continuation-in-part of design application Ser. No. 19,063, Sept. 8, 1969. This application Jan. 2, 1970, Ser. No. 20,736

Term of patent 14 years

Int. Cl. D7—99

U.S. Cl. D49—29

FIG. 1 is an elevational view of a combined bucket and closure therefor showing my new design;

FIG. 2 is an elevational view looking from the right of FIG. 1, the opposite side being the same appearance as the side shown;

FIG. 3 is a bottom plan view;

FIG. 4 is a top plan view;

FIG. 5 is a fragmentary sectional view taken substantially along line 5—5 in FIG. 3; and

FIG. 6 is a fragmentary sectional view taken substantially along line 6—6 in FIG. 4.

This application is a continuation-in-part of applicant's co-pending design application entitled Bucket With Clo-

sure, Ser. No. D. 19,063, filed Sept. 8, 1969 and now abandoned.

I claim:

The ornamental design for a combined bucket and closure therefor, as shown and described.
